DESIGN FOR A SKIRT

Morris Sobelman, St. Louis, Mo.

Application January 16, 1941, Serial No. 98,110

Term of patent 3½ years

To all whom it may concern:

Be it known that I, Morris Sobelman, a citizen of the United States of America, residing in St. Louis, city of St. Louis, and State of Missouri, have invented a new, original, and ornamental Design for a Skirt, of which the following is a specification, reference being had to the accompanying drawing, forming part thereof.

Fig. 1 is a front view of a skirt showing my new design.

Fig. 2 is a rear view thereof.

The characteristic feature of my design resides in the combination on the skirt disclosed of the pockets arranged on the front portion of the skirt, as shown.

I claim:

The ornamental design for a skirt, substantially as shown and described.

MORRIS SOBELMAN.
